DESIGN FOR WALL-PAPER.

SPECIFICATION forming part of Design No. 20,231, dated October 21, 1890.

Application filed September 27, 1890. Serial No. 366,396. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of ornaments of French rococo style forming repeating panels, with bunches of flowers in stencil inclosed in the panels between the ornaments, as represented in the accompanying photograph. The ornaments are composed 15 of connected ornamental scrolls and curves

arranged to form in outline an urn-shaped figure or ornament. The ornaments are joined together side by side, and the spaces between the ornaments are filled with bunches of flowers printed in stencil. The ornaments and flowers are printed in any desired color upon tinted paper of any desired color. 20

What I claim is—
The design for wall-paper herein shown and 25 described.

Witness my hand this 13th day of September, 1890.

CHARLES BOOZE.
